United States Patent Office.

J. A. ELSTON, OF ELSTON STATION, MISSOURI.

Letters Patent No. 67,739, dated August 13, 1867.

IMPROVED AERIAL MACHINE.

The Schedule referred to in these Letters Patent and making part of the same.

TO ALL WHOM IT MAY CONCERN:

Be it known that I, J. A. ELSTON, of Elston Station, in the county of Cole, and State of Missouri, have invented a new and improved Aerial Machine; and I do hereby declare that the following is a full, clear, and exact description thereof, which will enable others skilled in the art to make and use the same, reference being had to the accompanying drawings, forming part of this specification, in which—

Figure 1 is a perspective view of my improved machine.

Figure 2 is a top view of the same partly in section through the line $z z$, fig. 1.

Similar letters of reference indicate like parts.

My invention has for its object to furnish an improved machine for navigating the air, so constructed and arranged as to be completely under the control of the navigator; and it consists in the combination of one or more pairs of wings and the rods, slide, and lever, by means of which they are operated, with the frame of the machine, and in the combination of the eye-block and ropes with the bow and stern of the car for the purpose of adjusting the position of the car with respect to the supporting balloon; the whole being constructed and arranged as hereinafter more fully described.

A is the car, which I prefer to make boat-shaped, so as to encounter less resistance in moving through the air, and so as to be more under the control of the rudder. B is a central post securely attached to the frame of the car, and which is slotted vertically, with two slots crossing each other at right angles, as shown in figs. 1 and 2. To the upper end of the post are hinged or pivoted the pair or pairs of wings C. The wings C should be made somewhat concave, so that they may encounter less resistance in rising than in descending. Each wing may be a continuous plate, or it may be a framework covered with suitable material, and all the wings upon the same side should be connected together at or near their bases, so that they may move together. To the under side of the wings, near their bases, are attached arms D projecting downward, to the lower ends of which are pivoted the upper ends of the connecting-rods E, the lower ends of which are pivoted to the block F that slides up and down in the slots of the post B, as shown in fig. 1. To the under side of the sliding block F is pivoted the upper end of the connecting-rod G, the lower end of which is pivoted to the lever H, so that by moving the lever H up and down a movement is given to the wings C similar to that of a bird's wings in flying. The lever H passes through the slot in the post B, and is pivoted to a support I, attached to the frame of the car A. The ends h^1 and h^2 of the lever H extend beyond the post B and support I, so that it may be operated by a man at each end. The forward end h^2 of the lever H is curved, as shown in fig. 2, so that both the men that are operating the said lever may look forward. The car is designed to be attached to a balloon of such buoyant power as nearly to support the car and its contents; that is to say, of such power that the additional power developed by operating the wings C will easily cause the machine to rise. The car should be so connected to the balloon that its forward end may be raised above or lowered beneath the level of its rear end. J is an eye-block, by means of which the car is suspended from the balloon. K is a rope, the upper end of which is secured to the eye-block J, and its lower end to the stern-post of the car. L is a rope, one end of which is secured to the upper end of the post B; it then passes over a pulley in the eye-block J, and thence down to the forward end of the car over pulleys at the upper and lower parts of the post M, and has an eye or loop, N, attached to its end, by which it may be attached to one or the other of the teeth or hooks formed upon or attached to the rear side of said post, so that the forward end of the car may be raised or lowered, as desired. O is the rudder, which is pivoted to the stern-post P of the car, as shown in the drawings. R are ropes attached to the sides of the rudder O, which pass through eyes in the ends of the arms S attached to the stern-post P, through eyes in the ends of the arms T attached to the post B, and are attached to the steer-wheel U pivoted to the support I, as shown in fig. 1. By this arrangement of the steering apparatus the rudder O can be operated from either end of the car, as may be convenient.

In using the machine, when I wish to rise into the air I adjust the car so as to be upon a level, and work myself up to the desired height by using the wings. I then take the desired direction, and begin to descend by lowering the forward end of the car and move down a long inclined plane, descending either by gravity or by working the wings C, the force of which will now be backward and downward. Upon approaching the earth, if I wish to alight, I raise the forward end of the car above the level of the rear end. The force of the wings

will now be downward and forward, breaking the force of the momentum and alighting easily. But if I wish to ascend again I place the car upon a level and work up to the desired height with the wings. While being propelled either by gravitation or by the wings the rudder O enables me to direct my course as may be desired, which would not be possible if the machine floated with the wind.

Having thus described my invention, what I claim as new, and desire to secure by Letters Patent, is—

1. The combination of one or more pairs of wings C, connecting-rods E, sliding block F, connecting-rod G, and lever H, with each other, and with the post B and frame of the car, substantially as herein shown and described, and for the purposes set forth.
2. The combination of the eye-block J and ropes K, and L with the post B, and front and stern-posts of the car, for the purpose of changing the level of said car, substantially as herein shown and described.

J. A. ELSTON.
